UNITED STATES PATENT OFFICE.

HENRY BERRY, OF HUNTINGTON, CONNECTICUT.

DESIGN FOR A PITCHER, &c.

SPECIFICATION forming part of Design No. 16,538, dated February 23, 1886.

Application filed January 12, 1886. Serial No. 188,369. Term of patent 7 years.

To all whom it may concern:

Be it known that I, HENRY BERRY, a citizen of the United States, residing at Huntington, in the county of Fairfield and State of Connecticut, have invented a certain new and useful Design for Pitchers and other Similar Table Vessels; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

15 Figures 1 and 2 of the drawings are representations of this invention.

This design has relation to pitchers and similar table-vessels; and it consists in the novel form and configuration of the vessel, as 20 hereinafter shown and described. Expanding from the plain circular base A, the body B extends upward in spherical or ellipsoidal form to the junction with the neck portion C, which is of the form of an inverted conical frustum.

25 The body portion B is ornamented by means

of lines *b*, extending around its middle portion, and the neck portion C by means of similar lines extending around its lower portion at the junction with said body portion, as indicated at *c*. The neck portion C is further ornamented 30 by lines *d*, extending upward above the ornamental lines *c*.

Having described this design, what I claim, and desire to secure by Letters Patent, is—

The design for pitchers and similar table- 35 vessels, consisting of the spherical or ellipsoidal body B upon a plain circular base, A, ornamented by lines *b* around its middle portion, and surmounted by a neck portion, C, having the form of an inverted conical frustum, and 40 ornamented by lines *c*, extending around it at the junction with the body, and by lines *d*, extending upward from said lines *c*, as shown and described.

In testimony whereof I affix my signature 45 in presence of two witnesses.

HENRY BERRY.
